OIL FILLER CAP

Lewis L. Ruter, 218 26th Ave. N.,
Minneapolis, Minn. 55411

Filed Jan. 18, 1973, Ser. No. 324,777

Term of patent 14 years

Int. Cl. D15—01

U.S. Cl. D77—1 A

FIG. 1

FIG. 2

FIG. 3

FIG. 5

FIG. 4

FIG. 6

FIG. 7

FIG. 8

FIG. 9

FIG. 10

FIG. 1 is a side elevational view of the oil filler cap showing my new design;

FIG. 2 is a top plan view of FIG. 1;

FIG. 3 is a side elevational view of the right side of FIG. 1;

FIG. 4 is a side elevational view of the left side of FIG. 1;

FIG. 5 is a bottom plan view of FIG. 1;

FIG. 6 is a view similar to FIG. 3, partly sectioned to illustrate the interior of the oil filler cap;

FIG. 7 is a side elevational view of an oil filler cap showing a second embodiment of my new design;

FIG. 8 is a bottom plan view of FIG. 7;

FIG. 9 is a side elevational view of an oil filler cap showing a third embodiment of my new design; and

FIG. 10 is a bottom plan view of FIG. 9.

The top plan view of FIGS. 7 and 9 are identical to the top plan view shown in FIG. 2.

I claim:

The ornamental design for an oil filler cap, substantially as shown and described.
